STARTING CIRCUIT FOR ARC LAMP

Harry E. Schultz, Euclid, Ohio, assignor to General Electric Company, a corporation of New York

Filed May 2, 1957, Ser. No. 656,679

5 Claims. (Cl. 315—174)

This invention relates in general to a circuit for providing starting pulses of high voltage to an arc lamp in conjunction with a pulsed waveform operating circuit. Such a pulse-generating circuit may be used to effect the initial ionization of the discharge medium in the lamp, particularly where the breakdown voltage is of the order of several times the normal operating voltage of the lamp.

The invention is particularly useful with arc lamps of the kind frequently referred to as flashtubes, requiring a high instantaneous loading in order to have a high light output. When the instantaneous loading is high, the spectrum of the radiation produced contains, in addition to the usual line spectrum of the inert rare gas filling such as xenon, a continuum of radiation of substantial intensity whose over-all color is close to that of natural daylight. In flashtube or stroboscopic applications, the common method of energization of these lamps has been to charge a capacitor to a relatively high voltage, usually several hundred volts, which is then discharged through the flashtube connected across it. The discharge through the flashtube is initiated by applying a pulse to a triggering electrode which may take the form of a capacitive element disposed along the lamp, for instance a wire spiralled around the flashtube.

Where continuous pulsed operation of an arc lamp or flashtube is desired, the capacitor discharge method of operation has several limitations. In the first place it is basically inefficient by virtue of the losses in the system for charging the capacitor. In the second place, the residual ionization remaining in the lamp limits the rate of flashing or the loading below the level at which continuous conduction through the lamp prevents the build-up of charge in the capacitor.

In copending application Serial No. 656,595 of Emmett H. Wiley, filed of even date herewith, entitled "Pulse Circuit for Arc Lamp," and assigned to the same assignee as the present invention, there is described and claimed an alternating current pulsed operating circuit. This circuit uses a saturable reactor to provide high-intensity short duration current pulses for energizing an arc lamp or flashtube with high instantaneous loading and wherein the magnetizing current of the reactor is used to maintain ionization within the lamp between pulses. For economical design, the circuit must provide high-current pulses at a relatively low voltage generally insufficient to start the lamp though sufficient to repeat the pulsed discharge at cyclic intervals after initial ionization has been produced. It is therefore necessary to provide some means to effect initial ionization of the lamp for starting purposes.

The object of the invention is to provide a new and improved circuit for generating high-voltage starting pulses to effect the initial ionization of an arc lamp.

A more specific object of the invention is to provide a circuit combination which will generate high voltage and relatively low current pulses for starting a discharge within an arc lamp, and high current relatively low-voltage pulses for energizing the arc lamp with high instantaneous loading after initial ionization has been effected.

2

In accordance with the invention, the operating circuit for the discharge lamp comprises a main discharge current regulating loop and an auxiliary starting loop which induces high voltage pulses in a saturable inductor within the main loop. The auxiliary starting loop comprises a saturable inductor having a high-permeability core with a rectangular hysteresis loop characteristic. This inductor is connected, in series with a coupling winding on the saturable inductor of the main loop, across a capacitor charged from an alternating voltage source through a current limiting impedance. The capacitor discharges through the saturable inductor at the instant when saturation is reached and its incremental inductance falls substantially to zero. A high-current pulse thus occurs through the coupling winding which generates a high voltage pulse in the saturable inductor of the current regulating loop and thereby ionizes the arc lamp.

In a preferred embodiment, both the main discharge current regulating loop and the auxiliary starting loop use a saturable inductor having a high-permeability core with substantially rectangular hysteresis loop characteristic. The circuit of both the main loop and the auxiliary loop are similar, there being provided in each loop a T-network consisting of a current limiting inductor and a capacitor connected across an alternating voltage source. In the main loop, the saturable reactor is connected in series with the arc lamp across the capacitor. In the auxiliary loop, the saturable reactor is connected, in series with the coupling winding on the saturable reactor of the main loop, across the capacitor. At starting, the auxiliary loop produces high-current pulses through the coupling winding which induces high-voltage pulses in the saturable reactor of the main loop for ionizing the arc lamp. After the lamp has started, the saturable reactor of the main loop provides high-current pulses through the arc lamp resulting in the desired high instantaneous loading.

For further objects and advantages and for a detailed description of a preferred embodiment of the invention and its mode of operation, attention is now directed to the following description and accompanying drawing. The features of the invention believed to be novel will be more particularly pointed out in the appended claims.

In the drawing:

Fig. 1 illustrates diagrammatically an elongated arc lamp or flashtube with an operating circuit therefor embodying the invention.

Fig. 2 illustrates the rectangular hysteresis loop characteristic of the core material of the saturable reactors used in the circuit of Fig. 1.

Fig. 3 shows current and voltage wave forms in the circuit of Fig. 1.

Fig. 4 is a schematic diagram of a modified circuit embodying the invention.

Referring to the drawing and more particularly to Fig. 1, the circuit illustrated is designed for the operation of an arc lamp or flashtube F consisting of an elongated tubular quartz envelope 1 provided with activated thermionic self-heating electrodes 2 at opposite ends. Each electrode may consist of a tungsten wire helix 3 wound about the inwardly projecting end of the inlead and a thorium sliver disposed alongside. The inleads include foil portions 4 of molybdenum pinch-sealed through the end of the tube. The tube is filled with an inert gas such as xenon at a pressure below atmospheric pressure. As an example, arc lamp F may consist of a quartz tube 11" in over-all length, $\frac{1}{4}$ " in diameter, and with a xenon filling at a pressure of 40 mm. of mercury.

In the illustrated embodiment, both the main discharge current regulating loop and the auxiliary starting loop consist of similar reactive elements forming T-networks. The auxiliary loop is connected across input terminals T₁, T₂ adapted to be energized from a 120 volt, 60 cycle

supply. Closing switch S_1 connects reactor L_1 and capacitor C_1 in series across the voltage supply. L_1 is a substantially linear reactor and is shown as a winding 6 about the central leg of an E lamination 7 provided with an air gap at 8 next the end lamination 9 to prevent saturation of the core. A saturable reactor L_2 is connected across C_1 in series with a coupling winding L_5 wound about the core of a similar saturating reactor L_4 of the main current regulating loop.

In the main loop, closing switch S_2 connects reactor L_3 and capacitor C_2 in series across input terminals T_3 , T_4 adapted to be connected to a 280 volt, 60 cycle supply. Reactor L_3 , like reactor L_1 , is substantially linear in characteristics and is shown as a winding 10 on the central leg of an E lamination 11 provided with the usual air gap at 12 next the end lamination 13.

Saturable reactor L_4 is connected in series with the lamp F across capacitor C_2 , being for that purpose connected between one side of capacitor C_2 and output terminal T_5 while the other side of C_2 is connected directly to output terminal T_6 .

Both saturating reactors L_2 and L_4 are wound about toroidal cores 14 and 15 respectively, consisting of grain oriented silicon steel or nickel-iron strip continuously wound in the usual fashion to preserve the grain orientation parallel to the direction of magnetization. The magnetic core material is of a high-permeability, high-saturation flux density type having a rectangular hysteresis loop characteristic. Such a characteristic is illustrated in Fig. 2 showing the flux density B increasing very rapidly with the magnetizing force H up to the saturation levels S beyond which there is almost no further increase in flux density. Below saturation, the incremental permeability

$$\frac{\Delta B}{\Delta H}$$

is given by the slope of dotted line 16, whereas beyond saturation the incremental permeability is substantially that in air and equal to 1. The ratio of incremental permeabilities below and above saturation may be in the range of 10,000 to 1. Grain oriented silicon steel may be used for core 15 of L_4 and nickel iron having a yet smaller and more rectangular hysteresis loop is preferably used for core 14 of L_2 . Nickel iron core material of this type is sold under the various trade names Deltamax, Orthonol, and Permeron.

In the operation of the auxiliary starting circuit, when switch S_1 is closed, capacitor C_1 charges through linear reactor L_1 until its voltage is sufficient to saturate saturable reactor L_2 . The charging voltage wave form is shown by curve 21 of Fig. 3a; the charging occurs in a generally positive direction from time t_0 to t_1 , and in a generally negative direction from t_1 to t_2 . At the voltage level corresponding to t_1 , saturable reactor L_2 saturates. At this instant, its incremental permeability may drop by a factor of 10,000 and its inductive reactance falls through the same ratio. Accordingly, capacitor C_1 discharges rapidly through the saturable reactor providing the current pulse shown by curve 22 at time t_1 in Fig. 3b. This current pulse passes through winding L_5 on saturable reactor L_4 and the resulting rapid change in flux in the core induces a high-voltage pulse in main winding L_4 , shown by curve 23 at time t_1 in Fig. 3c. A half cycle later at time t_2 , the capacitor discharges in the opposite direction and produces the current pulse shown by curve 22 and the corresponding voltage pulse shown by curve 23. The interval from t_0 to t or t_1 to t_2 corresponds to $1/2$ cycle of the supply voltage shown by dotted line curve 24, namely $1/120$ second. The sequence of high voltage pulses applied across the arc lamp causes the xenon filling therein to become ionized.

Switch S_2 of the main current regulating loop may be closed at the same time as switch S_1 of the auxiliary starting loop, or at any time thereafter, in order to place the lamp F in normal operation. The main loop operates in

the same fashion as the auxiliary loop as regards the generation of the current pulses. However, its current pulses are used to energize the lamp directly rather than to provide high voltage pulses for the initial ionization. Capacitor C_2 charges through linear reactor L_3 until the voltage across it is sufficient to saturate the core of saturable reactor L_4 . At this instant, the inductance of saturable reactor L_4 drops approximately in the ratio of incremental permeabilities of the core below and above saturation.

10 This allows the charge across capacitor C_2 to be discharged in a short high-intensity pulse through the lamp. The discharge current wave form through the lamp is illustrated by curve 25 in Fig. 3d. The current pulses occur at times t_3 and t_4 twice per cycle, that is with a time interval of $1/120$ second apart. Times t_3 and t_4 may or may not correspond to times t_1 and t_2 , depending upon the adjustment of the circuit elements.

15 If the voltage-time integral of the charge across capacitor C_1 reaches the saturation level of saturable reactor L_2 early in the half-cycle of the supply frequency, the capacitor may recharge to the saturation level in time to generate one or more additional pulses within the half-cycle, as shown by dotted pulses 22', 22'' trailing main pulses 22 in Fig. 3b. This may be made use of in the auxiliary starting circuit to increase the speed with which the lamp is ionized. In the main discharge regulating loop, the voltage-time integral of charge across capacitor C_2 may likewise reach the saturation level of saturable reactor L_4 more than once during each half-cycle of the supply voltage.

20 The design criteria governing the choice of constants for the various circuit elements and the values selected for a unit actually constructed and found to operate under test as previously described are as follows.

25 The size of capacitor C_2 determines the loading or watt input into the lamp, and the voltage applied to terminals T_3 , T_4 must be sufficient to cause the discharge through the lamp to take place. If the applied voltage is too low, the discharge will not occur whereas if it is too high, unstable operation with multiple discharges and oscillations per half-cycle will occur as previously explained. For a loading of 1250 watts into the lamp previously described, a voltage supply of 280 volts with a value for C_2 of 42 microfarads is appropriate. Linear inductance L_3 must allow the recharging of capacitor C_2 to the operating value so that the voltage-time integral allows the build up of sufficient flux to exceed the saturation level of saturable reactor L_4 at each half-cycle. The value selected for L_3 is .04 henry and is achieved by approximately 165 turns on a core cross section $2'' \times 1\frac{1}{2}''$ measured at the winding leg of E lamination 11. The saturating reactor L_4 is chosen to saturate once per half-cycle at a voltage on the charging cycle above the maintaining voltage required for arc lamp F. In other words, the saturating reactor must have sufficient turns coupled with a cross sectional area achieving saturation on the charging cycle at or slightly above the striking voltage of the lamp. The saturating reactor used consists of 160 turns on a toroidal core of grain-oriented silicon steel $1\frac{3}{4}'' \times 1\frac{3}{4}''$ in cross section, 3" inner diameter and $6\frac{1}{2}''$ outer diameter.

30 In the auxiliary starting loop, the value of capacitor C_1 determines the energy transferred into the main current regulating circuit in the form of high-voltage ionizing pulses. The linear reactor L_1 is proportioned to allow capacitor C_1 to charge to the saturating level of saturating inductor L_2 at least once per half-cycle. In the unit constructed, C_1 has a value of 2 microfarads and L_1 has an inductance of approximately .17 henry giving a reactance of approximately 64 ohms at 60 cycles. Saturating inductor L_2 must have the necessary volt-ampere capacity to transfer sufficient pulse energy from capacitor C_1 into the main loop to achieve the necessary ionization in lamp F. In the unit constructed, L_2 consists of 200 turns on a toroidal core of high-permeability nickel-iron "Deltamax"

strip with a rectangular hysteresis loop characteristic, $1\frac{1}{2}'' \times 1''$ in cross section, $2\frac{1}{2}''$ inner diameter and $3\frac{1}{2}''$ outer diameter. Coupling winding L_5 consists of sufficient turns on the core of saturable reactor L_4 to obtain efficient transfer of energy along with substantial voltage multiplication. In the unit constructed, L_5 consists of 5 turns on core 13 of saturable inductor L_4 ; the winding ratio as between L_4 and L_5 is 160 to 5, providing a voltage multiplication of 32.

The circuit which has been described starts the illustrated lamp with pulses of approximately 3,000 volt peak amplitude at $\frac{1}{120}$ second time interval repetition, that is at 8,333 microsecond intervals. During normal operation, the arc lamp operates with a current pulse of approximately 77 amperes peak current and approximately 500 microsecond pulse width at 10 percent of maximum amplitude, the time interval between pulses being 8,333 microsecond, that is a repetition rate of 120 per second. The effective or R.M.S. value of current into the lamp is 13.6 amperes at a voltage drop of 117.5 volt and the energy input into the lamp is 1260 watts. The measured light output from the lamp is 34,530 lumens indicating an efficiency of 27.4 lumens per watt as regards the lamp and neglecting circuit losses.

Fig. 4 illustrates schematically a modification of the present circuit for operation on the ordinary 120 volt, 60 cycle A.C. supply generally available. Like reference numerals in this figure denote corresponding parts with reference to the circuit of Fig. 1. For ease of illustration all the circuit elements have been symbolically illustrated.

Both the main current regulating loop and the auxiliary starting loop are energized from terminals T_1 , T_2 adapted to be connected to the usual 120 volt, 60 cycle A.C. supply. The auxiliary starting loop is the same as has been illustrated in Fig. 1 and is energized upon the closure of switch S_2 through normally closed switch S_1 . The main discharge current regulating loop has been modified by the provision of an autotransformer 26 comprising a primary winding 27 and a high-reactance secondary winding 28 connected in series therewith across capacitor C_2 . The primary winding forms the input circuit of the transformer whereas the primary and secondary windings in series form the output circuit. The output circuit provides the necessary voltage for operating the lamp and at the same time the leakage reactance of secondary winding 28 serves the function of reactor L_3 previously described with respect to Fig. 1. If desired, switch S_1 may be a time delay relay which opens at a predetermined interval of time after energization of the circuit in order to disable the auxiliary starting loop after the lamp has started.

If desired one or more peaking stages each including a charging capacitor and a saturable inductor may be cascaded in either the main current regulating loop, as described in the copending Wiley application, or in the auxiliary starting loop, in order to achieve the desired steepness and intensity of pulse. In such case, the inductors and capacitors intervening between the input terminals and the final peaking stage together perform the current limiting function of the first inductor, that is L_1 in the auxiliary loop, or L_3 in the main regulating loop.

While the invention has been described in detail by reference to specific constructions embodying its principles, same are intended as illustrative examples and not in order to limit the invention thereto. The appended claims are intended to cover such modifications as will occur to those skilled in the art and coming within the true spirit and scope of the invention.

What I claim as new and desire to secure by Letters Patent of the United States is:

1. An operating circuit for an arc lamp comprising a pair of input terminals adapted to be connected to an alternating current source, a main discharge current regulating loop including a first capacitor and a first induc-

tor connected in series across said input terminals, a pair of output terminals adapted for connection to an arc lamp for pulse energization thereof, a first saturable inductor connected across said first capacitor in series with said output terminals, another pair of input terminals adapted to be connected to an alternating current source, an auxiliary starting loop including a second capacitor and a second inductor connected in series across said other input terminals, and a second saturable inductor having a high permeability core with a substantially rectangular hysteresis loop characteristic and a coupling winding on said first saturable inductor connected in series across said second capacitor to generate high-voltage pulses in said first saturable inductor for ionizing said lamp at starting.

2. An operating circuit for an arc lamp comprising a pair of input terminals adapted to be connected to an alternating current source, a main discharge current regulating loop including a first capacitor and a first current limiting inductor connected in series across said input terminals, a pair of output terminals adapted for connection to an arc lamp for pulse energization thereof with a residual current flow for maintaining ionization therein between pulses, a first saturable inductor having

20 a high permeability core with a substantially rectangular hysteresis loop characteristic connected across said first capacitor in series with said output terminals, another pair of input terminals adapted to be connected to an alternating current source, an auxiliary starting loop including a second capacitor and a second current limiting inductor connected in series across said other input terminals, and a second saturable inductor having a high permeability core with a substantially rectangular hysteresis loop characteristic and a coupling winding on said first saturable inductor connected in series across said second capacitor to generate high-voltage pulses in said first saturable inductor for ionizing said lamp at starting.

3. An operating circuit for an arc lamp comprising a pair of input terminals adapted to be connected to an alternating current source, a main discharge current regulating loop including a first capacitor and a substantially linear first inductor connected in series across said input terminals, a pair of output terminals adapted for connection to an arc lamp for pulse energization thereof with a residual current flow for maintaining ionization therein between pulses, a first saturable inductor having a high permeability core with a substantially rectangular hysteresis loop characteristic connected across said first capacitor in series with said output terminals, another pair of input terminals adapted to be connected to an alternating current source, an auxiliary starting loop including a second capacitor and a substantially linear second inductor connected in series across said other input terminals, and a second saturable inductor having a high permeability core with a substantially rectangular hysteresis loop characteristic and a coupling winding on the core of said first saturable inductor connected in series across said second capacitor, said first saturable inductor having a relatively high current ratio relative to said coupling winding whereby to generate high-voltage pulses in said first saturable inductor for ionizing said lamp at starting and thereafter permit relatively high current and low voltage pulse energization thereof by said main regulating loop.

4. An operating circuit for an arc lamp comprising a main discharge current regulating loop including a transformer having an input circuit for connection to an alternating voltage source and an output circuit including a high reactance secondary winding, a first capacitor connected across said output circuit, a pair of output terminals adapted for connection to an arc lamp for pulse energization thereof with a residual current flow for maintaining ionization therein between pulses, a first saturable inductor having a high permeability core with a substantially rectangular hysteresis loop characteristic

connected across said first capacitor in series with said output terminals, another pair of input terminals adapted to be connected to said alternating voltage source, an auxiliary starting loop including a second capacitor and a current limiting inductor connected in series across said other input terminals, and a second saturable inductor having a high permeability core with a substantially rectangular hysteresis loop characteristic and a coupling winding on said first saturable inductor connected in series across said second capacitor to generate high voltage pulses in said first saturable inductor for ionizing said lamp at starting.

5. The combination of an arc lamp comprising an elongated envelope containing an inert gas at a low pressure and having a pair of self-heating thermionic electrodes sealed into opposite ends, with an operating circuit comprising input terminals adapted to be connected to an alternating current source, a main discharge current regulating loop including a first capacitor and a first current limiting inductor connected in series across said input terminals, a first saturable inductor having a high permeability core with a substantially rectangular hysteresis loop characteristic connected across said first capacitor in series with said lamp for pulse energization

5
10
15
